UNITED STATES PATENT OFFICE.

BENJAMIN FURMAN LIVELY, OF LENOIR CITY, TENNESSEE, ASSIGNOR OF ONE-HALF
TO RAYMOND C. DUDLEY, OF CHICAGO, ILLINOIS.

CAR-ROOF.

1,351,256.

Specification of Letters Patent. Patented Aug. 31, 1920.

Application filed December 14, 1915. Serial No. 66,727.

To all whom it may concern:

Be it known that I, BENJAMIN F. LIVELY, a citizen of the United States, residing in Lenoir City, in the county of Louden and State of Tennessee, have invented a new and useful Improvement in Car-Roofs, of which the following is a specification.

The invention relates to metal car roofs, and has for its objects making the roof strong, rigid and self-sustaining, with the minimum number of roof frame members.

With such ends in view a principal part of the invention consists in the formation, combination and union of the roof sheets; the invention further consists in the parts and combinations thereof hereinafter set forth and claimed.

In order to make the invention more clearly understood there are shown in the accompanying drawings means for carrying the same into practical effect, without limiting the improvements, in their useful applications, to the particular constructions which, for the purpose of example, have been made the subjects of illustration. In the said drawings:

Figure 1 is a plan view of a portion of a car roof embodying the invention.

Fig. 2 is a side elevation of the same, partly broken away.

Fig. 3 is a vertical transverse section of one-half of the roof, from the eaves to the ridge, on a larger scale.

Fig. 4 is a plan view of one of the roof sheets.

Fig. 5 is a horizontal sectional view of the depending eaves end of one of the roof sheets, and portions of the contiguous interlocking roof sheets, on line V—V of Fig. 3.

Fig. 6 is a detail view, in vertical section, on line VI—VI of Fig. 1.

Fig. 7 is a view similar to Fig. 3, showing also the application and use of a carline with the said roof sheets.

Fig. 8 is a plan view of a portion of the roof, partly broken away, of the same construction as that shown in Fig. 7, and on a smaller scale.

Fig. 9 is a side elevation of the same, partly broken away.

Fig. 10 is a vertical transverse section of the eaves portion of the roof, on a larger scale.

Fig. 11 is a vertical transverse section of

the eaves portion of the roof, showing a 55 slightly different arrangement of the parts.

Fig. 12 is a vertical longitudinal section of the middle of the end portion of the roof, illustrating the same construction as Fig. 11.

Referring to the drawings, the roof frame 60 comprises side plates 1, which are preferably of Z-form, arranged so that the intermediate web 2 is horizontal with the outer flange 3 depending therefrom and the inner flange 4 upstanding therefrom. This gives a side 65 plate of great strength and provides upstanding flanges 4 to which the roof sheets (and also the carlines when they are employed) may be very conveniently and strongly attached. It will be understood 70 however that upstanding flanges on the side plates, to perform the roof sheet and roof frame holding function of the flange 4, may be provided in other ways, for instance by bolting an angle iron upon the top of a 75 wooden side plate.

The side plates 1 are supported by a suitable car frame, comprising preferably posts 5 and braces 6 united with each other and with the side plates by riveted brackets 7 80 (Fig. 2). The side plates are united at their ends by end plates 8 carrying end sheets 8' rounded on their upper edges to conform to the arch of the roof. The end plates are preferably of Z-form arranged similarly to 85 the side plates (Fig. 6).

The upstanding flanges 4 of the side plates are provided at suitable intervals with perforations 9 through which pass rivets 10 uniting the roof sheets with the side plates. 90

The roof sheets are shown at 11 formed of sheet metal heavier than that ordinarily employed in car roofs. These sheets are bent and formed by dies so as to be of arched form, from eaves to eaves of the roof, with 95 upstanding corrugations extending from end to end of the said sheets and transverse of the car. These corrugations are preferably of substantially rounded V-shape and of considerable depth or height, as indicated 100 (Fig. 5), and the intermediate or central corrugation 12 of each sheet is preferably of greater dimension than the other and marginal corrugations 13. Between the central large corrugation 12 and each marginal corrugation 13 is preferably formed one or more intermediate corrugations 14. When 105 the several sheets are combined together to

form a roof the marginal corrugations 13 of each sheet are interlocked with the corresponding marginal corrugations of the next sheet (Fig. 5), and the extreme margin 15 of the overlapping edge of each sheet is secured by rivets 16 with the underlapping portion of the next sheet. The marginal portions of the sheets are formed with a series, extending transversely of the car, of rivet holes 17 for this purpose.

The eaves ends of the roof sheets are bent to form vertical depending portions 18, which are also formed with the said corrugations, and which extend down at and against the outer faces of the side plate flanges 4, to which they are secured by said rivets 10 which pass through the perforations 17 formed at suitable intervals also in the said vertical portions of the roof sheets. 20 Certain of the rivets 16 which unite the roof sheets one to another may also pass through the flanges 4 of the side plates.

It is preferred that the bottom ends of the vertical portions 18 of the roof sheets shall rest firmly on the tops of the webs 2 of the side plates, thus giving a very stiff and solid support to the roof sheet arch.

Upon reference to Fig. 5 it will be seen that where one roof sheet is interlocked with another the corrugation is of double thickness and of corresponding strength and stiffness, and at the central part of each roof sheet, where there is no double corrugation, corresponding strength and stiffness are secured by making the central corrugation 12 of the considerable depth which is indicated.

The described roof sheets may be caused to aid in supporting one another under superimposed strains by means of the running board 20, the said running board being supported on saddles 21 to which it is bolted, and the said saddles being secured to the roof sheets at the seams thereof by any suitable means.

45 The only frame members comprised in the roof above described are the side and end plates. The invention does not however exclude the use of other frame members, where the latter are desired, and in 50 Figs. 7 to 10 are illustrated the combination and use of carlines with the said side plates and roof sheets. In this construction the side plates are composed each of two angle irons riveted together and arranged to form 55 horizontal webs and vertical depending and upstanding inner and outer flanges, as already described. But it will be understood that side plates of the construction shown in Fig. 3 may be employed.

60 The said carlines are indicated at 22 and are preferably of U-form in cross-section with lateral top flanges 23. These carlines are arched from eaves to eaves of the car to conform with the shape of the roof sheets 65 and are secured directly to the under sides

of the roof sheets by rivets 24. These carlines are or may be relatively few in number. As indicated in Fig. 8 there is one carline for each four roof sheets. The carlines are preferably applied under the roof sheet seams so that the rivets 16 which unite the roof sheets may also be passed through one of the carline flanges 23 and take the place of the said rivets 24, the latter being employed for that flange of the carline 75 which is at one side of the riveted roof sheet seam.

The carlines are further bent and formed at their ends so as to have vertical depending portions 25 the flanges 23 of which engage against the inner faces of the said plate flanges 4. Here they are preferably secured by said rivets 10 which pass through the said flanges 4 and also through the vertical portions 18 of the roof sheets. This construction and arrangement (Fig. 10) gives a very strong brace at intervals along the sides of the car at the spring of the roof sheet arch. In the construction illustrated in Figs. 7 to 10 a carline is applied at each 90 fourth roof sheet.

The corrugations of the sheets may be uniform, as indicated in Fig. 8. The end sheets 8' are formed with flanges 26 (Fig. 6) to which the end roof sheets are riveted 95 at 27 (Fig. 2).

The side plates 1 may be combined with and carried by wooden side plates 1' (Figs. 11 and 12), and the end plates may be of wood as shown in said figures at 30. The flange of the end sheet 8' may be bent back to include the projecting edge of the end roof sheet, as indicated at 31 in Fig. 12 and secured by rivets 32. The side sheathing is shown at 33 and the end sheathing at 34. 105 What is claimed is:—

1. In a metal car roof, in combination: roof sheets having upstanding transverse and V-shaped marginal corrugations, and having intermediate corrugations parallel 110 with and of greater depth than said marginal corrugations, the marginal corrugations of contiguous sheets being lapped and double at their apices; whereby the middles of the sheets are stiffened correspondingly 115 with their margins.

2. In a metal car roof, in combination, roof sheets having upstanding transverse marginal corrugations, and having between said marginal corrugations a corrugation of 120 greater depth than said marginal corrugations, the marginal corrugations of contiguous sheets being lapped on one another so that their apices are formed of double metal, the margin of the upper sheet being secured 125 to the body of the under sheet by a series of rivets near the marginal corrugations.

3. In a metal car roof construction, in combination: side plates having upstanding flanges, arched carlines engaging the inner 130

side of said flanges; arched roof sheets engaging the outer sides of said flanges; rivets directly uniting the top portions of said carlines and roof sheets; and rivets uniting together the carlines, the roof sheets and the interposed side plate flanges.

4. In a metal car roof, in combination: side plates having upstanding flanges along their inner portions; carlines arched from side to side of the car, said carlines having vertical end portions engaging the inner faces of the said flanges of the side plates and secured thereto; roof sheets over said carlines, arched from side to side of the car, formed with upstanding corrugations transverse of the car, the marginal corrugations of one sheet being lapped and interlocked with the marginal corrugations of the next sheets, and the overlapping margin of each sheet being riveted to the underlapping sheet, the roof sheets terminating at their ends in vertical depending eaves portions which are secured to the outer faces of the said flanges of the side plates; and rivets securing certain of said roof sheets to the carlines.

5. In a metal car roof, in combination: side plates having upstanding flanges along their inner portions; U-shaped carlines arched from side to side of the car and having lateral top flanges, said carlines having vertical end portions engaging the inner faces of the said flanges of the side plates and having their lateral flanges secured thereto; roof sheets over said carlines, arched from side to side of the car, formed with upstanding corrugations transverse of the car, the marginal corrugations of one sheet being lapped and interlocked with the marginal corrugations of the next sheets, and the extreme overlapping margin of each sheet beyond the marginal corrugation being riveted to the underlapping sheet, the roof sheets terminating at their ends in vertical depending eaves portions which are secured to the outer faces of the said flanges of the side plates; and rivets securing certain of said roof sheets to the side flanges of the carlines.

6. In a metal car roof, in combination: metal side plates of Z-form having upstanding side flanges along their inner portions; U-shaped carlines arched from side to side of the car and having side flanges, said car-

lines having vertical end portions engaging the inner faces of the said flanges of the side plates and having their side flanges secured thereto; roof sheets over said carlines, arched from side to side of the car, formed with upstanding corrugations transverse of the car, the marginal corrugations of one sheet being lapped and interlocked with the marginal corrugations of the next sheets, and the overlapping margin of each sheet being riveted to the underlapping sheet, the roof sheets terminating at their ends in vertical depending eaves portions which are secured to the outer faces of the said flanges of the side plates; and rivets securing certain of said roof sheets to the side flanges of the carlines.

7. A sheet metal roof sheet for car roofs, having near each side margin an upstanding corrugation, a central upstanding corrugation of greater depth and strength than said marginal corrugations, and corrugations between and parallel with said central and marginal corrugations.

8. A sheet metal roof sheet for car roofs, having near each side margin an upstanding V-shaped corrugation, a central upstanding V-shaped corrugation of greater depth and strength than said marginal corrugations, and V-shaped corrugations between and parallel with said central and marginal corrugations.

9. A sheet metal roof sheet for car roofs, having near each side margin an upstanding corrugation, a central upstanding corrugation of greater depth and strength than said marginal corrugations, and corrugations between and parallel with said central and marginal corrugations, said roof sheet being arched from side to side of the car and having vertical portions adapted to be connected with the side plates of the car frame, and said corrugations extending continuously along said vertical portions and said arched portion of the sheet.

In testimony whereof, I have hereunto set my hand in the presence of two subscribing witnesses.
